(57) **CLAIM**

The ornamental design for a soap pump as shown and described.

DESCRIPTION

FIG. 1 is a perspective view showing a soap pump of my new design in a first configuration;

FIG. 2 is a perspective view showing the soap pump of FIG. 1 in a second configuration;

FIG. 3 is a front view thereof (the rear view being identical);

FIG. 4 is a left side view thereof (the right side view being identical);

FIG. 5 is a top view thereof; and,

FIG. 6 is a bottom view thereof.

The dashed lines define the bounds of the claim and form no part of the claimed design.

1 Claim, 6 Drawing Sheets
